UNITED STATES PATENT OFFICE.

IRWIN F. HUEBNER, OF ALLENTOWN, PENNSYLVANIA.

MAILING DEVICE AND METHOD OF MAKING THE SAME.

Application filed June 18, 1923. Serial No. 646,097.

To all whom it may concern:

Be it known that I, IRWIN F. HUEBNER, a citizen of the United States, residing at Allentown, in the county of Lehigh and State of Pennsylvania, have invented certain new and useful Improvements in Mailing Devices and Methods of Making the Same, of which the following is a specification.

The present invention pertains to a combination mailing device comprising a fabric bag and a paper envelope permanently connected together at their edges, the one intended usually to receive comparatively small articles of merchandise or samples, and the other a written communication or the like.

Several forms of these devices are already on the market. In these, however, it is the practice to connect the bag, which is usually of fabric, and the envelope, which is usually of paper, by overlapping their marginal portions along one edge and stitching them permanently together. In addition to this, adhesive is sometimes used to more neatly and firmly secure the parts together. As a result of the rough handling to which such devices are subjected while in transit, the stitching is sometimes broken, or more frequently the stitching or other means of connection tears through the paper envelope and the containers are separated and lost. A common practice is to provide a fabric strip inside of the paper envelope with which the stitching engages when the containers are connected together, thus minimizing the likelihood of disconnection of the parts. This latter practice, however, adds not only to the number of parts to be assembled, thereby increasing the difficulties of manufacture on a quantity production basis, but also necessitates the use of additional material, all important factors in determining the price at which such a device is to be sold. Naturally, the price of a mailing device of this character must be quite small in order to render it salable in large quantities.

The primary object of the present invention is to produce a mailing device of the type described which is of a simple construction and thus easily manufactured and in which absolutely all unnecessary parts are done away with, consistent with the production of an efficient device, in order to reduce the cost of production to a minimum.

Reference is had to the accompanying drawing, wherein are illustrated several

forms of my invention, and in which the same reference numerals indicate like parts throughout the several views.

Figure 1 is a rear view of one form of the device with the fabric bag opened;

Fig. 2, a rear view during the stage of manufacture of the device, shown in Fig. 1, when the bag is inside out on the closed end of the paper envelope;

Fig. 3, a section on line 3—3 of Fig. 2, showing the manner in which the aligned edges of the bag and envelope are interlocked and secured;

Fig. 4, a section on the line 4—4 of Fig. 2;

Fig. 5, a front view of a modified form of the device; and

Fig. 6, a section on line 6—6 of Fig. 5.

In Figs. 1—4, inclusive, of the drawing, 1 represents an ordinary paper envelope having an open end 2 provided with a sealing flap 3 on which there is the usual marginal strip of adhesive 4. This envelope is adapted to receive the address of the addressee on its outer face, and to contain any first-class mailing matter or the like which it is desired to send to the addressee along with the article or articles in the other compartment of the device, after which it is sealed, as is well understood.

The bag member 5, which is to be connected to the closed end of the paper envelope 1 along one edge to close the bottom of the bag compartment so that it may receive such articles as it may be desired to send as parcel post, is formed from an elongated section or strip of fabric which is folded upon itself and the free edges thereof stitched together at 6 so as to form a tube having open ends 7 and 8. One of the open ends 7 of the tube has a marginal portion thereof turned inside of the tube and stitched down at 9 so as to form a pocket in which is located a draw-string 10 whereby the bag 6 may be temporarily closed at this end.

In manufacturing the device the tubular section of fabric described, that is, with the draw-string closing means provided at one end, and the other end left unfinished, is turned inside out and slipped over the closed end of the paper envelope 1 so that the edge of the unfinished end 8 of the fabric tube alines with the edge of the closed end of the envelope 1. A narrow marginal portion 11 of the unfinished end of the fabric tube and the enclosed end of the envelope 1 is then folded back together upon the body

portion of the envelope 1 and the body portion of the bag 5, as shown in Figs. 2 and 3. Securing means such as metallic fasteners 12 are then passed through the opposed folded 5 portions and the underlying body portions of the bag 5 and the envelope 1, thus firmly connecting the two together. If desired, a suitable adhesive may be used between these parts in addition to, or in lieu of, the securing 10 means mentioned to more permanently and neatly connect the parts together at the interlock thus formed between the container members.

The bag 5 is then stripped from the envelope 1, thus turning it right side out, as shown in Fig. 1, thereby not only concealing the unfinished end 8 of the fabric bag, but also the securing means connecting the bag and envelope together.

It will thus be seen that in the construction described, there is provided a strong connection between the fabric bag and the envelope, which is as efficient, if not more so, than this same connection between the 25 containers in devices of this character which are already in use and in which it is necessary, as heretofore stated, to provide a separate fabric strip within the closed end of the envelope in order to prevent tearing apart of the two members when subjected to rough 30 handling. By reason of the described interfolding of the adjoining overlapped edges of the bag and envelope members, in effect, the portion 13 of the fabric bag 5 which 35 is interposed between the folded marginal portion of the envelope 1 and its body portion, as shown in Fig. 3, serves the same purpose as does the separate reinforcing fabric strip used in the devices heretofore referred to, thus rendering unnecessary the usual additional step required to insert and 40 secure in place the reinforcing strip during the process of manufacture of these devices.

A modified form of the invention is disclosed in Figs. 5 and 6. The construction shown therein is intended to provide an even more secure interlock or connection between the envelope 1 and bag 5. This is accomplished by first placing the fabric bag member 5 inside out on the envelope 1, as hereinbefore described with reference to the form of the device shown in Figs. 1-4 inclusive. Then, a comparatively wide transverse marginal portion of the unfinished end of bag member 5, and the enclosed end of envelope 1 are folded back together on the body of the envelope and the body portion of the bag member. The free edge or marginal portion of this folded portion is then folded back upon itself so as to bring the free edge thereof substantially in alinement with the folded edge 14, as clearly shown in Fig. 6. The folded parts are then secured together by fasteners 12, as heretofore described, and the bag member stripped from the envelope. By

reason of this double inter-folding of the members a considerably strengthened connection between the bag and envelope is obtained, and there is less likelihood of fasteners 12 tearing through the paper envelope.

In some cases it has been found desirable to provide a separate card or strip on the device to receive the sender's and addressee's names and addresses, or perhaps certain advertising matter. Such a card is shown at 15 in Figs. 5 and 6. Before the above-described folding operation, card 15, in flat condition, is placed with its address-receiving face downward, between the front face 80 of envelope 1 and bag member 5, so as to bring one end thereof in alinement with the end of the envelope. The folding operation is then performed, thereby interfolding card 15 with the folded portions of the bag 85 member and the envelope, after which fasteners 12 are secured in place to connect together all of the folded parts of the device including card 15. When bag 5 has been stripped from the envelope, the main portion of card 15 is inverted and creased at 90 16 so as to bring its address-receiving face outward, the card then overlying bag 5 as shown in Fig. 5. Preferably card 15 is made of paper-faced fabric material so that 95 it serves the two-fold purpose of carrying certain printed or written matter and providing additional means for strengthening the connection between the bag and the envelope.

Numerous other modifications of the invention are contemplated, such as the substitution of envelopes and bags of types different from that shown, or any desired means may be used for connecting together 105 the adjoining edges of the members at the interlock. Hence it is not intended that the invention shall be restricted to the preferred construction described, except as the same may be limited by the appended claims.

What I claim is:

1. A mailing device comprising, in combination, a paper envelope having a marginal portion folded back upon the body portion thereof; a tubular bag member having a filling end and a marginal portion at its opposite end folded back upon the body portion thereof, one of said folded marginal portions being disposed between the other folded marginal portion and one of said body portions to form an interlock; securing means passing through said folded marginal portions and said last-mentioned body portion; and means for closing the filling end of the bag member.

2. A mailing device comprising, in combination, a paper envelope; an open-ended, fabric tube into one end of which projects an end of said envelope, said ends of the envelope and the tube being folded together

to form an interlock between the envelope and the tube and close said end of the fabric tube; securing means passing through said folded portions; and means for closing 5 the open end of the fabric tube.

3. A mailing device comprising, in combination, a flat, open-ended, tubular, fabric bag member having a marginal portion at one end of the member folded and contained within the body of the bag member, said marginal portion also being folded back upon itself within the bag member; a paper envelope having a marginal portion thereof projecting into said end of the bag member between the folds of said folded marginal portion of the bag member and extending with its free edge in substantial alinement with the free edge of said folded marginal portion of the bag member; securing 10 means passing through said folded marginal portions and the body portions of the envelope and the bag member; and means for closing the open end of the bag member.

4. A mailing device comprising, in combination, a paper envelope adapted to serve as a container for first-class mail matter; an open-ended, tubular, cloth member placed over the envelope inside out with one end of the envelope and one end of the cloth 25 member in end alinement with each other, the transverse marginal portion of said alined ends being folded back together and secured to the body portions of the envelope and cloth member to close said end of the cloth member, said member then being drawn off the envelope to serve as a separate container for parcel post matter; and means for releasably closing the opposite end of the cloth member.

5. A mailing device comprising, in combination, a paper envelope having a marginal portion folded back upon the body portion thereof; a tubular bag member having a filling end and a marginal portion at its opposite end folded back upon the body portion thereof, one of said folded marginal portions being disposed between the other folded marginal portion and one of said body portions to form an interlock; a data-receiving card having a marginal portion disposed between said last-mentioned folded marginal portion and said last-mentioned body portion; securing means passing through said folded marginal portions, said last-mentioned body portion and said marginal portion of the data-receiving card; and means for closing the filling end of the bag member.

6. The method of manufacturing double-compartment mailing devices comprising placing an open-ended, tubular bag member

inside out over the end of an envelope with the bottom end of said bag member substantially in alinement with said end of the envelope; folding back a marginal portion 65 along said end of the bag member, together with the enclosed portion of the envelope, upon the body portions of the envelope and the bag member; securing fastening means through said folded portions and the body 70 portions of the bag member and the envelope; and stripping the bag member from the envelope so as to turn it right side out and conceal said fastening means.

7. The method of manufacturing double-compartment mailing devices comprising placing an open-ended, tubular bag member inside out over the end of an envelope with the bottom end of said bag member substantially in alinement with said end of the envelope; folding back a transverse marginal portion along said end of the bag member, together with the enclosed portion 75 of the envelope, upon the body portions of the envelope and the bag member; folding the free transverse marginal portion of said folded portion back upon itself; securing fastening means through all of said folded portions and the body portions of the bag 80 member and the envelope; and stripping the bag member from the envelope so as to turn it right side out and conceal said fastening means.

8. The method of manufacturing double-compartment mailing devices, comprising inserting an envelope within an open-ended, tubular cloth member so as to bring an end of said envelope in substantial transverse alinement with one end of the cloth member, the cloth member being turned inside 95 out; placing a data-receiving card, face downward, between the envelope and the cloth member with one of its ends in alinement with said alined ends of the cloth member and envelope; folding back a transverse marginal portion of all of said alined ends upon the body portions of the envelope and the cloth member; folding the free marginal portion of said folded portion 100 back upon itself so as to bring its free edge in alinement with said first-mentioned fold; securing fastening means through all of 105 said folded portions and the body portions of the bag member, the envelope and the card; stripping the bag member from the envelope so as to turn it right side out and conceal the fastening means; and turning the free portion of said data-receiving card 110 so as to bring it face outward.

In testimony whereof I have signed my name to this specification.

IRWIN F. HUEBNER.
